Primary Examiner — Karen Kearney*Assistant Examiner* — John M. Otte(74) *Attorney, Agent, or Firm* — Banner & Witcoff, Ltd.(57) **CLAIM**

The ornamental design for a display screen with animated icon, as shown and described.

DESCRIPTION

FIG. 1 is the first image in a sequence for a display screen with animated icon showing our new design;

FIG. 2 is the second image thereof;

FIG. 3 is the third image thereof; and,

FIG. 4 is the fourth image thereof.

The appearance of the animated icon sequentially transitions between the images shown in FIGS. 1-4. The process or period in which one image transitions to another forms no part of the claimed design. The broken line showing of the remainder of the display screen forms no part of the claimed design.
